UNITED STATES PATENT OFFICE.

JOHN DESMOND, OF WILMETTE, ILLINOIS, ASSIGNOR TO WILLIAM S. POTWIN, OF CHICAGO, ILLINOIS.

FLEXIBLE PISTON-ROD AND CYLINDER THEREFOR.

1,106,930.

Specification of Letters Patent. Patented Aug. 11, 1914.

Application filed November 11, 1912. Serial No. 730,581.

To all whom it may concern:

Be it known that I, JOHN DESMOND, a citizen of the United States, residing at Wilmette, in the county of Cook and State 5 of Illinois, have invented certain new and useful Improvements in Flexible Piston-Rods and Cylinders Therefor, of which the following is a specification.

My invention relates to improvements in 10 apparatus involving a flexible piston-rod to one end of which the piston is permanently secured.

One of the salient objects of my invention is to provide a flexible piston rod where- 15 by to transmit the movement of a piston, within a cylinder, to some exterior instrumentality, thereby to avoid the necessity for excessive linear space wherein to contain the piston rod, of the usual rigid type, when 20 it is projected from the cylinder.

Other, and more specific, objects of my invention will become readily apparent, to persons skilled in the art, from a consider- 25 ation of the following description when taken in conjunction with the drawings, wherein:

Figure 1 is a broken away, plan view, of 30 an engine starting device, showing the admissible compactness of parts when my im- proved piston is employed; Fig. 2 is an en- 35 larged side elevation of the same, part in section, taken on line 2—2 of Fig. 1; Fig. 3 is a longitudinal central section of the cyl- 40 inder and piston, showing the manner of use of my improved piston rod; and Fig. 4 is a cross section taken on line 4—4 of Fig. 3.

In all the views the same reference char- 45 acters are employed to indicate similar parts.

In my copending application, for start- 50 ing devices for internal combustion engines, Serial No. 692,250, filed April 22, 1912, there is shown the disadvantage of rigid piston rods, of the usual type; the cylinder, con- 55 taining the piston, being located a full cyl- inder length away from the parts to be op- erated by the piston rod.

It is the purpose of my present invention 60 to provide a piston rod, of a flexible nature, whereby the cylinder may be located rel- atively close to the apparatus to be oper- ated by the movement of the piston rod.

In this application similar reference let- 65 ters have been employed for indicating simi-

lar parts contained in my previous applica- 55 tion, whenever consistent so to do.

5—5 are the side frame members of an ordinary automobile.

6 is an engine of the internal combustion type, which is not self starting, and 7—7 60 are the arms by which the engine is sup- ported upon the side frame members, as at 8—8.

11 is the shaft of the engine. Carried on 65 the shaft is a spider, or three armed struc- ture 16, secured thereto by means of a key 15. At the ends of the arms 22, are pivot- ally secured weighted ratchet pawls 17, 18 70 and 19, which are yieldingly held in engage- ment with the teeth on the ratchet wheel 20, by means of springs 21. A ratchet wheel, 20, is secured to, or is a part of, the drum 23. A smaller drum, 24, is mounted on an axle 25, and a connecting rope or band 26 75 is secured to the drum 24 and is also wound at least once around the drum 23 and se- cured thereto. The drum 24 carries a spring, which exerts its yielding influence toward winding up the cable, or band 26, around the drum 24. A power cylinder 28, 80 adapted for use in connection with a com- pressible fluid such as air, or gas, contains a longitudinally movable piston 29 which is connected to my flexible and improved pis- 85 ton rod 30. The piston rod is preferably made of a thin flexible steel ribbon, similar in many respects, to a clock spring, so that it may be readily wound around the drum 23, and it is wound around the drum 23 at least one time, and firmly secured thereto. 90 The cylinder, 28, is firmly secured to one of the side frames 5 as by a bracket 31 and an orifice 32, is the opening through which the power fluid medium is admitted into the 95 cylinder.

When the fluid under pressure is admitted 100 to the cylinder 28, as through the opening 32, in front of the piston 29, it has the effect of driving the piston to the opposite end of the cylinder and thereby rotating the drum 105 23 causing the shaft 11 to be rotated, which positively turns the ratchet wheel 20, and by the engagement of the pawls 17, 18 and 19, with the said ratchet wheel, the spider 16 and the shaft 11 are rotated primarily, and prior to, the self operation of the engine. After the engine becomes self operative the spider on the shaft 11 will be positively

driven at a higher velocity than the drum 23 and the centrifugal effect thus produced will cause the pawls 17, 18 and 19 to fly out free of the teeth in the wheel 20, and when this is done the spring, contained in the drum 24, will rotate the drum 23 in the opposite direction to that in which it has been rotated by the piston, the drum 23, now being relieved, by the outward movement of the 10 pawls, from its association with the shaft 11 and the spider 16, and thereby the piston 29, through the medium of the flexible piston rod 30, being wound around the drum 23, will be again brought to the front end of the 15 cylinder 28, in its normal operative position.

In Fig. 4 I have shown a packing gland 33, secured in position, as by studs, or screws 34, by means of which the packing 35 is held in the receptacle 36 provided in the head 37 of the cylinder 28. The means for packing the flexible piston rod is in every respect similar to that for packing a round piston rod with the difference that the arrangement is formed in conformity with the difference 20 in the cross sectional shape of the two pistons.

The movement of the piston 29, of the cylinder 28, during its power stroke is such as to straighten out the flexible piston rod 30, and to exert a straight pull on it, and when it is moved in the opposite direction, as by means of the spring contained in the drum 24, the tendency is to maintain the piston rod 30 in a straight line, and in no instance 35 is the power so applied as to have any tendency to buckle the piston rod, and the application of power in each instance tends to elongate rather than compress or shorten the rod and for this reason the piston rod is in every respect satisfactory and operative for 40 the purpose of transmitting power. Its flexible nature permits of the location of a cylinder near to the drum 23, as shown, and therefore, lends itself to the compactness of 45 operation and simplicity of construction.

I do not limit my improvement for use solely in connection with automobiles, as many situations in which it may be employed with equal advantage will readily occur to 50 one versed in the art.

What I claim is:

1. In a device of the character described the combination, of a flexible ribbon adapted

to have its end connected to some part to be moved, a piston permanently secured to one free end of said ribbon, a cylinder for said piston, and a head for said cylinder, said cylinder having near said head an opening for admission of fluid under pressure, whereby the admission of fluid under pressure between said head and piston draws the ribbon within the cylinder, and a packing means for said ribbon carried by said head, whereby the latter is rendered air-tight. 55

2. In a device of the character described the combination of a flexible ribbon constituting a means adapted to be wound around a wheel to be rotated, a piston permanently connected to one end of said ribbon, a cylinder within which said piston is adapted to 70 work, a head for said piston, a packing gland carried by said head through which the ribbon works to render said head air-tight, and means associated with said cylinder for admission of fluid under pressure 75 between said piston and air-tight head, whereby there is provided a piston rod adapted to lie in a straight line while within the cylinder and adapted to lie in a curve for coaction with said wheel when drawn without the cylinder. 80

3. In a device of the character described the combination of a cylinder, a head for said cylinder inclosing the same to provide therein an air-tight piston-receiving space, a piston in said cylinder, a flexible piston rod permanently secured to said piston, and a packing gland carried by said head adapted and arranged to receive said flexible piston rod, whereby admission of fluid under pressure between said air tight head and movable piston moves the piston rod inwardly, said piston adapted and arranged to be returned to normal position by extraneous means associated with the other end of said ribbon, the ribbon therefore lying always in a straight line while within the cylinder but adapted and arranged to conform to the periphery of an extraneous device to be moved thereby. 85

In testimony whereof I hereunto set my hand in the presence of two witnesses.

JOHN DESMOND.

In the presence of—

W. LINN ALLEN,

MARY F. ALLEN.
